(57) **CLAIM**

The ornamental design for a notebook computer, as shown and described.

DESCRIPTION

FIG. 1 is a perspective view of the notebook computer according to a first embodiment of the present design;

FIG. 2 is a front view of the thereof;

FIG. 3 is a rear view of the thereof;

FIG. 4 is a left-side view of the thereof;

FIG. 5 is a right-side view of the thereof;

FIG. 6 is a top view of the thereof;

FIG. 7 is a bottom view of the thereof;

FIG. 8 is a perspective view of the notebook computer according to a second embodiment of the present design;

FIG. 9 is a front view of the thereof;

FIG. 10 is a rear view of the thereof;

FIG. 11 is a left-side view of the thereof;

FIG. 12 is a right-side view of the thereof;

FIG. 13 is a top view of the thereof; and,

FIG. 14 is a bottom view of the thereof.

The broken lines shown in the drawings illustrate portions of the notebook computer that form no part of the claimed design.

1 Claim, 14 Drawing Sheets
